BUILDING CONSTRUCTION

Robert L. Pinney, Toledo, Ohio, assignor to
 Libbey-Owens-Ford Glass Company, Toledo,
 Ohio, a corporation of Ohio.

Application January 5, 1938, Serial No. 183,409

2 Claims. (Cl. 189—34)

The present invention relates broadly to building constructions, and more particularly to interior and exterior wall structures, partitions, and the like.

5 An important object of this invention is the provision of a wall or partition made up of preformed building units which can be easily and quickly assembled and likewise disassembled whenever desired.

10 Another important object of the invention is the provision of preformed building units of novel and improved construction, together with means for connecting said units in interlocking relationship to form the wall or partition without the aid of mortar, cement, or the like.

15 A further important object of the invention is the provision of preformed building units of exceptionally pleasing and attractive appearance; which are of relatively simple, inexpensive 20 construction; and which may be conveniently and economically assembled on the job to provide a wall or partition of sturdy, durable construction.

25 A still further important object of the invention is the provision of building units of the above character adapted for association with one another to form a self-sustained wall or partition, each unit comprising a metal frame and spaced 30 inner and outer ornamental facing panels carried thereby and providing an intervening air space which serves to prevent or reduce transmission of heat, thereby resulting in a wall or partition having relatively great insulating value.

35 Other objects and advantages of the invention will become more apparent during the course of the following description, when taken in connection with the accompanying drawing.

40 In the drawing, wherein like numerals are employed to designate like parts throughout the same:

Fig. 1 is a perspective view of a portion of a wall structure made up of building units embodying the invention;

Fig. 2 is a horizontal sectional view through a portion of a wall section;

Fig. 3 is a perspective view of one of the improved building units;

Fig. 4 is a perspective view of one of the key members for interlocking the building units together; and

Fig. 5 is a detail sectional view taken substantially on line 5—5 of Fig. 1.

With reference now to the drawing and particularly to Fig. 1, the letters A and B designate 55 two wall sections, partitions, or the like, disposed

at substantially right angles to one another and each being made up of a plurality of preformed building units 10 constructed in accordance with the invention. The building units 10 are laid up in courses in much the same manner as brick, 5 cut stone, or the like, with the units of one course being supported directly upon the units of the next lower course. The building units are also constructed in such a manner that they can be easily and quickly assembled on the job to form 10 a self-sustained wall, partition, or the like without the use of mortar, cement, or other cementitious material, as will be more clearly herein-after apparent. The building units forming the bottom course of the wall or partition are supported upon and interlocked with a base plate 11, while the units forming the top course may have associated therewith a top plate similar to bottom plate 11. The units at the opposite ends of the wall or partition are preferably interlocked 15 with corner posts 12.

20 Although the units 10 have been illustrated in the drawing and will be hereinafter described as being rectangular, it will be readily appreciated that the invention is not limited to any particular shape or size of unit. Briefly, each unit 10 comprises a metal frame 13 and inner and outer ornamental facing panels 14 and 15 carried 25 thereby, the intervening air space 16 serving to prevent or reduce transmission of heat. The ornamental facing panels 14 and 15, while being of any desired material, preferably consist of sheets or plates of flat glass either transparent, translucent, or opaque and decorated or not as 30 desired. The facing panels may also be of any suitable color or colors and may be either of ordinary glass or tempered glass to increase the 35 strength of the unit.

When making rectangular units, the metal 40 frame 13 preferably comprises four sections of rolled or extruded metal arranged at the four edges of the facing panels 14 and 15 and cooperating to form a frame extending entirely around the perimeter of the unit, said sections 45 being mitered and welded, soldered, or otherwise suitably secured together at the four corners of the unit as indicated at 17. Each metal section consists of a base member 18 disposed between the facing panels 14 and 15 and provided along opposite side edges thereof with U-shaped channel portions 19 and 20 for receiving the adjacent edges of the facing panels therein. Extending inwardly from the peripheral edges of the channel portions 19 and 20 are flanges 21 and 50 55

22 respectively arranged outwardly of and parallel with the base member 18 and connected thereto by the web portions 23 and 24. The flanges 21 and 22 project beyond the web portions 23 and 24 to provide lips 25 and 26 which cooperate with said web portions and also with said base member to provide a recessed portion 27 in the form of an undercut channel. The facing panels 14 and 15 can be either firmly secured at their edges in the channel portions 19 and 20 of the metal frame 13 or can be loosely received therein. The numeral 28 is used to designate either a suitable cementitious material for securing the facing panels to the metal frame or cushioning strip to allow for expansion and contraction of the facing panels, especially if they are of glass.

As brought out above, the units 10 are adapted to be interlocked with one another when in assembled position and the means provided for this purpose consists of elongated key members 29 which, as shown in Fig. 4, are substantially H-shaped in cross section and composed of the tongue portions 30 and 31 joined by the web portion 32. As best illustrated in Fig. 3, the lips 25 and 26 of the metal frame sections terminate at their opposite ends inwardly of the flanges 21 and 22 to provide the cut-out or notched portions 33 at the corners of the unit which permit the key members 29 to be associated therewith in the manner to be hereinafter described.

In assembling the preformed units 10 to form a wall section, the units forming the bottom course of the wall are first laid end to end upon the base plate 11 which has been previously properly positioned after which key members 29 are inserted downwardly between the vertical side edges of adjacent units as shown in Fig. 2, with the tongue portions 30 and 31 of said key members being received in the recessed portions or undercut channels 27 of said adjacent units to secure them together. The units are also interlocked with the base plate 11 by the use of horizontal key members 34, similar to key members 29, and which are received within the undercut channels 27 in the bottoms of the units and similar undercut channel 35 in said base plate. Additional units are then laid one upon the other until a wall of the desired width 50 and length has been formed. During the assembling of the units, vertical and horizontal key members are interposed between and interlocked with the metal frames 13 of vertical and horizontal adjacent units. The units are thus supported directly upon one another and connected together without the use of mortar, cement, or the like. The units at each end of the wall are preferably connected to a corner post 12, said corner post being provided with vertical undercut channels 36 which correspond to the undercut channels 27 in the adjacent vertical edges of the units and which receive key members 29. The units forming the top course of the wall may have associated therewith a top plate similar to bottom plate 11 so that the wall will be anchored at the top, bottom and opposite ends thereof. As shown in Fig. 1, the wall sections A and B extend at substantially right angles to one another but they may be arranged at any desired angle by simply modifying the shape of the corner post 12.

The units 10 may be utilized in the construction of both interior and exterior walls as well as for partition walls. These units can be pre-formed at the factory and shipped to the job

where they can be easily and quickly assembled. Furthermore, they can be readily disassembled whenever desired. The provision of ornamental facing panels 14 and 15 will eliminate the use of plaster or interior decoration. Also, by providing ornamental facing panels of glass or other light-transmitting material, the walls may be illuminated by lighting means enclosed within the wall structure. The units being hollow will allow for greater structural utility, even containing heat stacks, chutes and electrical wiring, all hidden behind the facing panels. In addition, the provision of hollow units, with an intervening air space between the inner and outer facing panels results in a wall of relatively great insulating value, in that the said air space prevents or reduces transmission of heat.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In a wall structure, a wall section comprising hollow building units arranged in courses and freely supported one upon the other, each of said units being composed of a plurality of metal sections associated with one another to form an integral substantially rectangular frame, and facing panels for the opposite sides of said frame, each metal section of said frame comprising a base member disposed between the facing panels for spacing the same from one another and provided along opposite side edges thereof with substantially U-shaped channel portions for receiving the adjacent edges of said facing panels therein, flanges extending inwardly from the peripheral edges of the channel portions outwardly of and substantially parallel with said base member and connected thereto by transverse web portions, said flanges projecting beyond said web portions to provide lips which cooperate with the said web portions and also with the said base member to provide a recessed portion in the form of an undercut channel, and key members inserted between the vertical and horizontal side edges of adjacent units and having tongue portions received within the undercut channels in the metal frames of said units to secure them together.

2. In a wall structure, a wall section comprising hollow building units arranged in courses and freely supported one upon the other, each of said units being composed of a plurality of metal sections associated with one another to form an integral substantially rectangular frame, and facing panels for the opposite sides of said frame, each metal section of said frame comprising a base member disposed between the facing panels for spacing the same from one another and provided along opposite side edges thereof with substantially U-shaped channel portions for receiving the adjacent edges of said facing panels therein, flanges extending inwardly from the peripheral edges of the channel portions outwardly of and substantially parallel with said base member and connected thereto by transverse web portions, said flanges projecting beyond said web portions to provide lips which cooperate with the said web portions and also with the said base member to provide a recessed portion in the form of an undercut channel,

and key members inserted between the vertical and horizontal side edges of adjacent units and having tongue portions received within the undercut channels in the metal frames of said units to secure them together, the said lips of the metal frame sections terminating at

their opposite ends inwardly of the respective flanges to provide notched portions at the corners of the unit so that the vertical and horizontal key members may be properly associated therewith.

ROBERT L. PINNEY.
